UNITED STATES PATENT OFFICE.

ARTHUR E. MEYER, OF CHICAGO, ILLINOIS.

PROTECTED COMMERCIAL PAPER.

1,174,753.

Specification of Letters Patent.

Patented Mar. 7, 1916.

Application filed October 4, 1915. Serial No. 54,083.

To all whom it may concern:

Be it known that I, ARTHUR E. MEYER, a citizen of the United States, residing at Chicago, in the county of Cook and State 5 of Illinois, have invented certain new and useful Improvements in Protected Commercial Papers, of which the following is a specification.

The present invention relates to a means 10 for treating commercial paper, such as bank checks, notes, etc., in a manner to prevent the alteration of any part thereof.

The principal objects of the invention are to provide a process for carrying out the 15 above purpose, which can be applied easily and quickly, and applied with equal efficiency irrespective of the manner in which the written portions of the paper are arranged.

20 A further object of the invention is to provide means whereby all of the written portions of the paper are protected against alteration.

The invention further consists in the features of construction and combination of 25 parts hereinafter described and claimed.

In the drawings: Figure 1 is a face view of the bank check protected in accordance with the teachings of the present invention; 30 and Fig. 2 is a longitudinal section of such check.

In the art to which the present invention relates, there have been a variety of ways and means disclosed for treating commercial paper, so as to prevent an erasing of a portion thereof and a subsequent alteration, or otherwise changing the tenor of the paper. But the methods now commonly employed necessitate the use of complex 35 machinery and are not adapted to prevent erasures of all portions of the filled in or written part of the check, and are directed toward that portion wherein the amount is stated.

40 I consider it to be very advantageous to provide means for protecting all written portions of the paper, this principally by reason of the fact that such paper is arranged to bring the written portions into 45 different relative arrangement and location,

and with the devices now used, of which I am aware, a material written portion of the paper will not be protected in any way.

By the present invention, a protection of all of the written portions of the paper 55 against alteration is provided for, irrespective of the manner in which said written portions may be arranged.

Referring now to the drawings, the invention is shown as applied to a bank 60 check 3, which can be of suitable size and nature, and can be arranged, as to the printed and written matter thereon, in any way desired. After this check has been filled in, that is, the name of the payee and 65 the amount written in, and signed by the payor, the paper is submitted to a treatment of any suitable mechanical appliance, which will place a series of corrugations 4 across the entire surface of the same at a single 70 operation. By thus corrugating the entire surface of the paper, not only is the means for insuring against alteration of the amount quickly and easily applied, but all 75 portions of the check or paper will be so treated. Consequently, there is no danger of leaving any important portion of the written part of the paper unprotected, nor to accomplish this need the written portion 80 of the check be arranged in any particular 80 manner. Therefore, irrespective of the arrangement of the written matter on the paper, or the form or character thereof, by corrugating the entire surface of the paper, the check is protected against alteration 85 of any written portion, thus eliminating the danger of leaving certain portions exposed and unprotected, and eliminating any clerical error in placing the protection where it would be unavailing. 90

By so protecting the paper, in accordance with the present invention, it is possible to obtain the protection without the use of any complicated or expensive machinery. The protection can be obtained equally as 95 well whether the matter inserted in the check is written by hand or upon the type-writer; and the operation which is required for protecting is of a nature which is very quickly and easily applied, entailing prac- 100

tically no more work than would be entailed in the filling in of the check.

I claim:

5 A bank check or similar commercial paper, comprising an unpunctured body formed with regularly occurring corruga-

tions extending entirely across that portion of the paper within the confines of which written matter is placed, substantially as described.

ARTHUR E. MEYER.
